UNITED STATES PATENT OFFICE.

ANDREW LITTLE, OF NEW YORK, N. Y.

DESIGN FOR TYPE.

SPECIFICATION forming part of Design No. 16,124, dated June 9, 1885.

Application filed March 18, 1885. Term of patent 7 years.

To all whom it may concern:

Be it known that I, ANDREW LITTLE, of the city, county, and State of New York, have invented and produced a new Design for a Font of Printing-Type, of which the following is a specification.

The nature of my design is fully shown in the accompanying typographic impression, to which reference is made; and it consists of a script letter of the running-hand character, the upper and lower portions of which are made heavier than the rest of the letter, so that a contrast may be presented between the heavy and light portions of the letters. In the A, B, 15 D, P, and R the up-and-down portion of the letter does not extend to meet the rounding portion of the letter, but terminates below the same, as shown. The face of the A, C, E, G, L, and S is crossed by the light inclined line 20 extending from the upper right-hand termination of the letter to and beyond the base of the letter upon the left. In the B, D, P, and R the up-and-down portion of the letter is ornamented upon the left by a light inclined line 25 extending from the upper portion of the same, and this feature characterizes the F, H, K, M, N, T, U, V, W, X, Y, and Z upon the left of the upper portion of the same.

The character of the design is preserved in 30 the lower-case, the numerals, and punctuation-marks, save that the light inclined line crossing the face of the A, C, E, G, L, and S is omitted.

My design differs from the patent of John K. Rogers, No. 14,963, in that the features named— 35 a combination of heavy and light lines, a light inclined line crossing the letter, and a light inclined line following the up-and-down portion and cross portion of the letters—do not occur therein, and also from the design patented by John West, No. 15,610, in that the bases of the letters are rounding and not straight, the light inclined line crossing the letter is not found in the West design, and that the up-and-down portion of the F, G, H, 45 I, J, K, T, and Y do not terminate in a straight line, as shown in the West design.

Having now described my invention, I claim as new—

The design for a font of running-hand script type herein described and shown, the same consisting of a letter the upper and lower portions of which are heavier than the rest of the letter, the up-and-down portions of which do not extend to meet the rounding portion of the letter above them, the A, C, E, G, L, and S of which are crossed by a light inclined line, as shown, and the majority of the letters being provided with a short light inclined line, forming a continuation upon the left of the up-and-down and cross portions of the letters.

ANDREW LITTLE.

In presence of—

W. V. H. HICKS,
A. SIDNEY DOANE.
